JOHN VAN BRUNT, OF FLUSHING, NEW YORK, ASSIGNOR TO INTERNATIONAL COMBUSTION ENGINEERING CORPORATION, OF NEW YORK, N. Y., A CORPORATION OF DELAWARE

FINELY-DIVIDED-FUEL-BURNING BOILER FURNACE

Application filed May 5, 1926. Serial No. 106,813.

This invention relates to boiler furnaces, and is particularly useful where the fuel is to be burned in suspension, as, for example, where the fuel is in pulverized form.

5 The invention has to do with that type of boiler which is constructed in the shape of a furnace, and is, in fact, its own furnace, and one of the primary objects of the invention is to simplify and cheapen the construction as well as decrease the size thereof, as will further appear. I obtain the foregoing, together with such other objects and advantages as may hereinafter appear, or are incident to my invention, by means of a construction which I have illustrated in the preferred form in the accompanying drawings, wherein—

Fig. 1 is a vertical section thru a boiler furnace embodying my invention, and

20 Figs. 2 and 3 are fragmentary front and side elevations of a modification of the invention.

Referring now to Fig. 1, the reference character A denotes the boiler furnace considered as a whole. The boiler defines the combustion space proper B beneath which there is an ash pit C formed by the setting 7 which serves to carry the boiler.

In the main, the boiler comprises the four 30 drums 8, 9, 10 and 11; the front water wall a composed of longitudinally finned tubes 12, the lower ends of which are connected into the drum 9 and the upper ends of which are connected into the drum 11; the side

35 water walls b composed of longitudinally finned tubes 13, the lower ends of which are connected into the headers 14 and the upper ends of which are connected into the headers 15, the headers 14 being connected into the

40 drum 8 and the headers 15 being connected into the drum 11; the roof water wall c composed of finned tubes 16, the lower ends of which are connected into the drum 10 and the upper ends of which are connected into

45 the drum 11; the rear water wall d composed of longitudinally finned tubes 17, the lower ends of which are connected into the drum 8, and the upper ends of which are connected into the drum 10; the bank of 50 tubes 18, the lower ends of which are con-

nected to the drum 8, and the upper ends of which are connected into the drum 9; the vertical bank of tubes 19, the upper ends of which are connected into the drum 10 and the lower ends of which are connected into the drum 8; the equalizing drum 20 and the equalizer tubes 21 and 22, which connect drums 11 and 20. Feed water is supplied to the drum 10 by means of pipe 10^a. The drum 10 is also provided with a baffle 10^b forming a chamber into which the steam from the tubes 17 of the upright wall d is delivered and from which chamber the steam is led by the tubes 16 of the roof wall c.

The bank of tubes 18 bounds the bottom of the combustion space and the tubes are spaced apart a sufficient distance to allow any refuse particles precipitating out of the fuel to pass therebetween to the ash pit C. This bank of tubes serves the function of cooling such precipitating ash below slag forming temperature. The products of combustion are drawn off between these tubes and pass downwardly into the chamber below the tubes and thence into the chamber 23 from which they are passed over the vertical bank of tubes 19, suitable baffling being associated with the bank of tubes 19. The products of combustion pass from the bank of tubes 19 at 24 into the breeching 25 in which is located the combustion air pre-heater 26.

It will be observed that the bank of tubes 19 constitutes the economizer section of the boiler and that this economizer section by virtue of its tubes connecting the boiler drums 8 and 10 is an integral part of the boiler. It is also to be noted that by this arrangement the economizer tubes become the downcomers of the boiler, the circulation in the tubes of the tubular walls being in an upward direction. Thus the necessity for the usual outside downcomer tubes is obviated and I am therefore enabled to shorten the length of the drums, and do away with the usual lagging for the tubes and consequently reduce the width of the boiler and the cost of manufacture and also loss by radiation.

A superheater 27 is located between the bank of tubes 19 and the rear tubular water wall *d* of the boiler which superheater is subject to the combustion gases passing from the combustion chamber to the breeching 25, the gases, altho cooled sufficiently by the bank of tubes 18 to prevent fusion of the ash, still being of sufficient temperature to superheat the steam passing thru the superheater, and to provide the necessary heat for the combustion air.

At the four corners of the combustion space and preferably at the upper portion thereof I have provided the burners 28 for introducing the fuel to be burned. Highly preheated combustion air is introduced with the fuel thru the medium of the air openings 29 surrounding the burner nozzles, the preheated air being taken from the air preheater 26 hereinbefore mentioned by the ducts 30 leading from the preheater to the burners. Thus the fuel and air is introduced in a manner to produce vortical mixture and combustion, the combustion being intense and turbulent, whereby a high flame temperature and short length of flame travel is obtained.

Referring now to the modification illustrated in Figs. 2 and 3 it will be seen that each of the tubes 12 of the front wall of the combustion chamber connect into separate headers 31 instead of connecting into a common drum as shown in Fig. 1. The tubes of the bank of tubes 18 connect the headers 31 with the drum 8, whereby the bank of tubes 35 is divided into a plurality of vertical rows of tubes 32, the number of which is increased or diminished in accordance with the degree of temperature of the exit gases desired.

It will be noted that by locating the superheater as shown, a high degree of superheat is obtained and the temperature of the gases is somewhat lowered this temperature being further lowered by the economizer section whereby the temperature of the gases at the air heater is kept below the point at which the air heater plates or elements would be burned.

I claim:

1. In combination, a boiler furnace having its side and end walls comprised of upright tubular water walls upper and lower drums and upper and lower headers, the tubes of the end walls being connected into said upper and lower drums, the tubes of the side walls being connected into said upper and lower headers, the upper headers being connected to an upper drum and the lower headers being connected to the opposite lower drum, said tubular water walls being subject to radiant heat and the tubes of the economizer

section being subject to the heat of convection of the gases of combustion.

2. In combination, a boiler furnace having its side and end walls comprised of upright tubular water walls upper and lower drums and upper and lower headers, the tubes of the end walls being connected into said upper and lower drums, the tubes of the side walls being connected into said upper and lower headers, the upper headers being connected to an upper drum and the lower headers being connected to the opposite lower drum, a roof water wall comprising water tubes connecting the aforesaid upper drums, tubes connecting the aforesaid lower drums, and economizer tubes which also constitute the sole downcomer for the boiler directly connecting the lower and upper drums of the rear end wall, said tubular water walls being subject to radiant heat and the tubes of the economizer being subject to the heat of convection of the gases of combustion.

3. In combination in a pulverized coal burning boiler furnace, a furnace shaped boiler comprising front and rear walls formed of upper drums, lower drums and water tubes connecting said drums; side walls formed of upper headers, lower headers and water tubes connecting said headers, said upper headers being connected into the upper drum of the front wall and said lower headers being connected into the lower drum of the rear wall; a roof wall formed of water tubes connecting said upper drums; tubes marginal of the bottom of the boiler connecting said lower drums; and a bank of tubes spaced from the water tubes of the rear wall directly connecting the upper and lower drums of said rear wall and constituting the sole downcomers for the boiler.

4. In a pulverized fuel burning installation, a boiler shaped furnace comprising a pair of upper drums, a pair of lower drums, front and rear tubular water walls composed of upright tubes respectively connected into the front upper and lower drums and the rear upper and lower drums, side water walls composed of upright tubes connected with the rear lower and front upper drums, an upper water wall composed of tubes connected into the upper drums, tubes connecting the lower drums, economizer tubes which also constitute the sole downcomers for the boiler, directly connected into the rear upper and lower drums and spaced away from the rear water wall, superheater elements in said space, an offtake beyond said economizer tubes, an air heater in said offtake, pulverized fuel burners, and means for delivering the preheated combustion air from the preheater to the combustion space defined by the boiler.

5. The combination with a boiler furnace having its combustion space largely defined by upright tubular water walls connected

into the circulation of the boiler, of an upper and a lower drum, tubes of the rear end wall being connected to said upper and lower drums, a bank of substantially upright 5 economizer tubes connected to said upper and lower drums, said bank of tubes being spaced away from the tubes of the rear end wall, and a superheater in the space between the said bank of economizer tubes 10 and tubes of the rear end wall, means whereby fuel may be burned in suspension in said combustion space with the gaseous products of combustion passing downward and around said lower drum, a baffle in the lower 15 portion of said bank of economizer tubes directing said gases through said bank of economizer tubes from the rear thereof to the said space in which the superheater is located, the said superheater being shielded 20 from the radiant heat of the combustion space by the tubes forming the rear end wall of the furnace.

6. The combination with a furnace shaped tubular boiler having an upper drum to 25 which the tubes of the boiler are connected, substantially all of said tubes being exposed to radiant heat, of a bank of convection tubes, an upper drum to which the upper ends of said convection tubes are connected, means connecting said first drum 30 with said latter drum comprising a plurality of substantially horizontal tubes some of which connect the upper portion of the two drums and others of which connect the two drums at a lower point, and 35 means connecting the lower ends of the said convection tubes to the tubes of the furnace shaped boiler.

7. In combination a furnace shaped boiler 40 the side walls of the combustion chamber thereof including rows of substantially upright tubes subject to radiant heat, means connecting the upper ends of said rows of tubes to a common drum, a bank of convection tubes, an upper drum to which the 45 upper ends of said convection tubes are connected, means connecting said first drum with said latter drum and means connecting the lower ends of the said convection tubes 50 to the tubes of the furnace shaped boiler comprising a drum to which tubes of each group are directly connected.

In testimony whereof, I have hereunto signed my name.
